UNITED STATES PATENT OFFICE.

JOHN F. O'CONNOR, OF CHICAGO, ILLINOIS, ASSIGNOR TO WILLIAM H. MINER, OF CHAZY, NEW YORK.

INSULATION FOR REFRIGERATOR-CARS AND THE LIKE.

1,345,391.

Specification of Letters Patent.

Patented July 6, 1920.

Application filed December 20, 1916. Serial No. 137,962.

To all whom it may concern:

Be it known that I, JOHN F. O'CONNOR, a citizen of the United States, residing at Chicago, in the county of Cook and State of Illinois, have invented a certain new and useful Improvement in Insulations for Refrigerator-Cars and the like, of which the following is a full, clear, concise, and exact description, reference being had to the accompanying drawings, forming a part of this specification.

This invention relates to improvements in insulation for refrigerator cars and the like.

15 The object of the invention is to provide an efficient insulation for refrigerator car doors and other similar uses and which is composed of a minimum number of parts; which may be easily applied; and which produces a wide surface bearing between the adjacent members to be sealed as contradistinguished from a line of contact.

20 In the drawing forming a part of this specification, Figure 1 is a horizontal sectional view of portions of a refrigerator car and doors, showing the improved insulation applied thereto, the doors being in closed position. Fig. 2 is an enlarged sectional view of one of the members provided with 25 the insulation and showing the latter in normal or uncompressed condition. Fig. 3 is a view similar to Fig. 2, but illustrating the position of the parts under compression. And Fig. 4 is an elevational view of one of 30 the members provided with the insulation, part of the fabric being cut away to illustrate interior construction.

35 In said drawing, 10 denotes a wall of a refrigerator car having the door opening 40 therein, the latter being closed by the two hinged doors 11 and 12, the former being closed first and the latter closed last on account of the arrangement of meeting beveled edges, as indicated at 13.

45 The improved insulation is applied between the meeting edges of the doors and also between each door post and corresponding door. Inasmuch as the insulation is the same for all places, it will only be necessary 50 to describe it for one. Referring now more particularly to Figs. 2, 3 and 4, 14 designates a groove or channel extending longitudinally of the member to which the insulation

is applied, said groove being relatively shallow and having a plain, flat bottom. Bridging said groove is a layer of quilting or felt 55 15 which is tacked to the wood as by the tacks or nails 16. Outside of the quilting or felt is a layer of canvas or duck 17 which is held by said nails 16 and also by outer 60 additional series of nails 18. The layers of fabric material are yieldingly supported by my improved packing strip which, as shown, comprises a strip of sheet metal loosely placed in the groove 14 and having the 65 edges thereof provided with reversely extending curls 19 and 20. The plate is made of spring material so as to provide a yieldable support for the fabric and in cross section, the supporting strip may be said to 70 be of substantially S shape. It will be noted from an examination of Figs. 2 and 3, that the fabric is supported along two parallel spaced lines as indicated at 21—21 and the supporting strip also engages the bottom of 75 the groove along two parallel spaced lines, as indicated at 22—22. In this way, a strong but yielding support is supplied for the fabric along two spaced parallel lines which will insure keeping that portion of the 80 fabric between the two lines of contact 21—21 stretched taut and prevent formation of pockets in the fabric which might permit transmission of air through the insulation. The normal condition of the spring 85 strip is as shown in Fig. 2, that is, with portions of the strip extended out beyond the face of the member in which the groove is provided. When the doors are forced to closed position, it is apparent that the 90 fabric will be pressed down and the spring strip compressed, thus resulting in the curled edges of the spring strip being decreased in diameter, as indicated in Fig. 3.

95 I claim:

An insulation for refrigerators and the like which comprises, in combination, a member having a groove with a plain bottom extending longitudinally along one edge thereof, a layer of flexible material 100 bridging said groove, and a spring plate loosely mounted within said groove, said spring plate being of substantially S-shape in cross section with each edge curled, said curled edges being normally of such diameter as to each have longitudinally extending

line bearing against the bottom of the groove and against the flexible material to force the latter along two lines outwardly beyond the edge of said member, said curled edges being compressible and thereby maintaining said line bearing contacts between the flexible material and the spring plate and be-

tween the spring plate and the bottom of the groove.

In witness that I claim the foregoing I 10 have hereunto subscribed my name this 16th day of Dec., 1916.

JOHN F. O'CONNOR.
